UNITED STATES PATENT OFFICE.

HOWARD SMALL, OF ATLANTIC CITY, NEW JERSEY, ASSIGNOR TO JAMES H. BELL, OF PHILADELPHIA, PENNSYLVANIA.

PNEUMATIC PUMPING APPARATUS.

1,199,030.

Specification of Letters Patent. Patented Sept. 19, 1916.

Application filed November 11, 1910, Serial No. 591,760. Renewed February 12, 1916. Serial No. 78,069.

To all whom it may concern:

Be it known that I, HOWARD SMALL, a citizen of the United States, residing at Atlantic City, in the county of Atlantic and 5 State of New Jersey, have invented certain new and useful Improvements in Pneumatic Pumping Apparatus, of which the following is a specification.

My invention relates to a pneumatic 10 pumping apparatus in which the inclosing casing forms a vacuum chamber, which is connected, by tubing or hose, with any desired type of suction nozzle or sweeper adapted to be employed for cleaning cars 15 pets and the like.

One object of my invention is to provide a novel form of pumping mechanism, which is located within the vacuum chamber, and comprises two pumping or pulsation chambers, preferably opposed to each other and 20 connected together by tubes which form a support and also means of communication between the same.

A further object of my invention is to 25 provide a vibrating member in each of the pulsation chambers and a motor suitably connected with said vibrating members for operating the same.

A still further object of my invention is 30 to provide a single inlet valve in one of the pulsation chambers to supply air to both of said chambers and a single outlet valve to exhaust the air from both of said chambers.

A still further object of my invention is 35 to provide a novel form of pumping mechanism having a plurality of pumping chambers, pumping mechanism coöperating with the pumping chambers and a motor for operating the pumping mechanism, the parts 40 being assembled in such a manner that they form a unit of structure which may be readily removed from the inclosing casing.

A further object of my invention is to devise a novel method of pumping in which 45 I employ a plurality of pulsation chambers, the fluid passing from one pulsation chamber through the other pulsation chamber to the atmosphere or a desired point of utilization.

50 In order that those skilled in the art will be able to readily comprehend my invention I have shown different adaptations of my invention to illustrate some of the ways in which my invention may be practically

carried out and advantageous results obtained but as will be apparent the arrangement of the instrumentalities employed may be varied and still be within the spirit and scope of the invention.

Figure 1 is a sectional elevation of a 60 pumping apparatus embodying my invention; Fig. 2 is a vertical section on line 2—2 Fig. 1; and, Fig. 3 is a sectional elevation of another embodiment of my invention.

65 Similar numerals of reference indicate corresponding parts in the figures.

Referring to the drawings: Referring first to Fig. 1, 1 represents a casing forming a vacuum chamber 2, closed at its ends by a 70 base 3 and a top or cover 4. The vacuum chamber 2 contains the separating device 6 and the pumping casing 7 with the electric motor 8 for operating the same.

The base 3 is preferably circular in form, 75 supported by legs 10 and provided with bolts 12, having nuts 13 for engaging projecting-lugs 14, upon the collar 15, secured to the lower end of the casing 1, whereby the base 3 and the casing 1, may be clamped 80 together and made air-tight by a suitable gasket 16.

The upper portion of the casing 1 is provided with a collar 18 which is secured to said casing, and said collar is provided with 85 bolts 19 and nuts 20 for clamping the cover 4 to the casing. Between the cover and the collar 18 on the casing is clamped the outwardly turned flange of the sleeve 22, which supports the separating device 6. Gaskets 90 23 and 24 are clamped between the said parts to make the joints air-tight.

The cover 4 receives the inlet pipe 26 and the elbow on the end of the said pipe 26 is turned so as to deliver the inrushing air 95 tangentially against the depending flange 28, secured to the under side of the cover.

The separating device consists of the above described sleeve 22, to which is attached a bag 6, preferably made of fabric, 100 for the purpose of filtering the dust laden air and thereby purifying it. At the bottom of the separating device is provided a wire ring 29, for the purpose of keeping the fabric extended and also for the further 105 purpose of preventing the separating device from being pressed against the wall of the casing. It is desirable that the air passing

through the separating device shall pass through the sides thereof to a free passageway around the outside of the separating device, to the inside surface of the casing, 5 thereby providing a large space for the passage of air through the separating device, so as to avoid the tendency of the current of air slowing down the motor and thereby lessening the pressure exerted on the separating device at the time the volume of air is passing through it, as the velocity of the air will be in proportion to the enlarged area of the separating device.

It is preferable that the separating device 15 does not reach the bottom of the vacuum chamber and it is made sufficiently short in the present instance to form a space below it for the free passage of air.

The vacuum chamber contains the pumping casing 7, which in this embodiment is supported upon the base 3, which latter may if desired form the lower portion of the pumping mechanism.

The pumping mechanism consists of a 25 plurality of pulsation chambers and for purposes of illustration I have shown two pulsation chambers 30 and 31 which are connected by passageways or tubes 33, which permit the free passage of air or fluid between said chambers. The shells 35 and 36, forming the pulsation chambers 30 and 31, are rigidly secured together by means of bolts 38, which engage the top surface of the upper shell 35 and the bottom surface 30 of the lower shell 36 and pass through the tubes 33, thus clamping the parts rigidly together.

The motor 8 is located between the pulsation chambers 30 and 31 and is mounted 40 upon a base 40, having legs 41, which latter rest upon or form part of the ring 42, which is secured to the upper surface of the shell 36 of the lower pulsation chamber 31. The legs 41 are curved to form ample space for 45 the movements of the vibrating member 45, of the lower pulsation chamber 31.

The upper pulsation chamber 30 is provided with a valve 46 of any desired type and the lower pulsation chamber 31 is provided with a valve 47 of any desired type. Said valves are similar in construction in the present instance and consist of a rigid disk 48, preferably made of metal, and a flexible disk 49 preferably made of leather. 50 Each of the disks 48 and 49 has apertures 50 and 51 respectively formed therein, and arranged in staggered relation so that when the flexible disk 49 is in contact with the metal disk 48 the apertures 50 in the rigid disk 48 will be closed by the solid portion of the flexible disk 49, thus forming a check-valve which acts automatically.

When the higher pressure is upon the side 60 of the valve, where the flexible disk is located, the valve will close, and when the

higher pressure is upon the side of the valve, where the rigid disk is located, the valve will open and allow the air to flow through the same. The parts of said valves are clamped together by screws 53 or other suitable fastening devices. There is provided a supporting-web 54, located a short distance from the leather disk 49, to prevent the same from having too much movement.

The under side of the shell 35 of the upper pulsation chamber 30 and the upper side of the shell 36 of the lower pulsation chamber 31, are each provided with circular openings, which are closed by the vibrating members 45 and 55. The vibrating members 45 75 and 55 are similar in construction and each consists of a disk 57, to which is clamped a flexible collar or diaphragm 58, made preferably of leather. The outer edge of the diaphragm 58 is secured to the pulsation 80 chamber by means of metal rings 42 and 59, held rigidly by screws 60, or other fastening devices, and the inner edge of the diaphragm 58 is secured to the disks 45 and 55 by means of rings or collar 61, secured by 85 screws 62, or other suitable fastening means. The flexible diaphragms 58 permit the disks to vibrate freely.

The disks 45 and 55 are provided with lugs 63 and 64 having stud-shafts 65 and 66, 95 to which are operatively connected the ends of the connecting-rods 68 and 69, the opposite ends of the latter embracing eccentrics 70 and 71, upon the motor shaft 73. The ends of the connecting-rods are preferably 100 connected with the stud-shafts 65 and 66 in such a manner that a non-pivotal connection is formed although slight relative lateral movement may be permitted if desired. Ball-bearing connections are provided in 105 said eccentrics to reduce the friction. The eccentrics are located at each end of the motor-shaft 73 and are arranged in pairs, one pair being connected to opposite sides of the disk of the vibrating member 45 and 110 the other being connected to the opposite side of the disk of the vibrating member 55.

The connecting-rods and eccentrics are so set that the vibrating members move simultaneously in opposite directions, one up and one down, thus causing both pulsation chambers to act in unison.

The air discharging from the pump may exhaust directly to the atmosphere or if desired a casing 74 may be employed which 115 is retained in assembled position by the rods 38 and provided with ports 75 thereby serving as a muffler.

In the embodiment seen in Fig. 3 I have shown the pump unit as supported in a 125 novel manner and a different manner of separating the impurities from the air. Since many of the parts seen in Fig. 3 correspond to those seen in Figs. 1 and 2, I have designated like parts by their corre-

sponding reference characters and I have deemed it unnecessary to describe in detail such construction as the same would involve needless repetition.

5 76 designates the inlet port which is adapted to receive the suction hose, the air passing tangentially into the vacuum chamber 2, the lower end of which is closed by the end member 78, suitably connected with 10 the legs 10 and preferably of conical form so that the dust and foreign material separated from the air may be readily removed by actuating the movable member 79, which in the present instance is pivotally mounted 15 at 80.

The bolts 12 are carried by the bottom member 78 which latter is suitably adapted to receive the packing 81, which engages one side of the flanged ring 82. The annulus 15 in this embodiment is adapted to receive a packing 83 whereby the parts are assembled in air tight condition.

The flanged member 82 is provided with a groove 84 in which is adapted to be seated a preferably resilient ring 85 to which a suitable skeleton framework 86 is connected over which the filtering material 6 is stretched in order to give greater area to the filter and to cause the dust and dirt to 25 fall from the separating device by gravity into the precipitation chamber formed by the base of the machine. In this embodiment the pump unit is suspended within the vacuum chamber and in order to illustrate one manner of accomplishing this I have shown the pump unit as having a cross-bar 87 retained in position by the fastening devices 53 and adapted to receive an eye-bolt or connection 88 to which one end 30 of a spring 89 is secured, the other end of such spring being secured to a cross-bar 90 which is held in position by fastening devices 91, the latter also serving to hold in position the flexible member 92, the outer periphery of which is secured by means of suitable fastening devices 93 with a flexible member 94, the inner periphery of which latter is secured to the pump unit by means 35 of the fastening devices 53. The cover in 40 this case is provided with a discharge opening 95 which if desired may be covered by the muffler casing 74. The purpose of the spring 89 is to support the pump unit in such a way that no vibration caused by the 45 pump unit or the pumping mechanism will be communicated to the casing and the pump unit is free to swing laterally. This spring I have shown as being located in the air passage formed by the flexible member 92 and 94 but in the broad scope of my 50 invention the pump unit is yieldingly suspended in the vacuum chamber and is not necessarily carried by the casing cover as shown.

65 The operation of the embodiment of my

invention seen in Fig. 1 is as follows: A pipe or flexible hose having an ordinary suction nozzle or sweeper at its end is connected with the intake pipe 26 of the vacuum cleaner. The motor contained within the 70 casing 1 is rotated by connecting the same with an ordinary electric lighting circuit for its source of current. The vibrating members of the pumping device are reciprocated rapidly, by the connecting-rods upon 75 the shaft of the motor. The effect of this is to force the air from the two pulsation chambers 30 and 31 of the pumping device, out through the exhaust valve 47, thus reducing the air pressure in the pulsation 80 chambers which will cause the air at atmospheric pressure in the vacuum chamber to open the inlet valve 46, causing a vacuum in said vacuum chamber which will draw the dust laden air through the intake pipe 85 26, which will strike tangentially against the flange 28, upon the cover and thus avoid injuring the fabric of the separator. The dust is collected upon the inner surface of the separator and the air purified 90 by being strained through the fabric of the separators, through which latter it freely passes to the inlet valve 46 of the pumping device from which it escapes into the chamber 70 in case such is employed, the same 95 acting as a muffler to reduce the sound of the escaping air.

The cover may be readily removed by loosening the thumb-nuts and the separating device may be lifted from the casing for 100 the purpose of removing the dust that has been collected within the same.

By my improved construction of the pumping device it will be noted that there are no valves in the vibrating members and 105 that they, therefore, together with the connecting-rods, can be constructed in such a way as to secure lightness, which is desirable, owing to the rapid movements of the vibrating members, which if constructed 110 heavily, must cause increased oscillation or tilting, and the lighter this construction can be made, the less the oscillation or tilting will be from their rapid reciprocatory movements.

115 The pumping device, herein described, includes the novel feature of a plurality of pulsation chambers, each operating with a vibrating member, said chambers having free communication each with the other, and using preferably only one set of valves, inlet and outlet, for the plurality of chambers. This is conducive to simplicity of construction and facilitates a balanced operation of the motor as related to the pumping mechanism, inasmuch as the load is equalized from both sides of the motor shaft and at the same time the pressure or load contributed by each of the pulsation chambers is equal, owing to the fact that they freely commun-

cate and the air pressure or load in each pulsation chamber is equalized by the freely communicating passages.

The motor being located between the two pulsation chambers and the fact that the eccentrics are so set that the vibrating members move simultaneously in opposite directions one up and one down, the effect is to cause the pulsation chambers to act in unison, whereby at one stroke of the vibrating members the two pulsation chambers are filled with air from the vacuum chamber 7, taken through the valve 46, located in the top of the upper pulsation chamber, thus filling the upper chamber 30 and through the pipes 33, also the lower pulsation chamber 31, and with the reverse action of the connecting-rods and vibrating members, discharging the contents of both pulsation chambers 30 and 31 from the lower pulsation chamber through the single valve 47 located in the lower part of the lower pulsation chamber 31. The contents of the upper pulsation chamber being discharged through the tubes 33, heretofore mentioned, through the lower pulsation chamber 31, simultaneously with the contents of the lower pulsation chamber and through the exhaust valve 47 at atmospheric pressure, either direct to atmosphere or through the casing 74 having small apertures 75. The casing 74 is secured to the under side of the base 3 and acts as a muffler, to equalize the discharge of air and thereby prevent noise. The chamber 74 is not intended to be used as a pressure chamber but as a muffler only and may be dispensed with if desired.

In the embodiment seen in Fig. 3 the dust laden air enters tangentially through the inlet 76 and passes through the dust separating device 6, the heavier particles falling by gravity to the bottom member 78, this action being facilitated owing to the variations in pull on the filtering fabric due to the fluctuations in the vacuum. The air in its purified condition passes through the pump in the same manner as hereinbefore described and thence through the port 95 to the atmosphere or point of utilization.

If each pulsation chamber were an independent pump, having an inlet and an outlet valve there would at all times be a difference in the load, owing to the fact that it would not be practical to have the valves of each pump operating exactly the same. Therefore, it would be certain that in practical operation, one pump would be doing more work than the other, and the opposing loads as related to the motor would be unequal, which would contribute to strain and vibration.

It has been demonstrated that for practical purposes there is a limitation to the size of the diaphragm pump, both as to stroke and as to the diameter of the pump itself.

The stroke of the diaphragm pump is limited, but for practical purposes, owing to the fact that the length of the stroke must be provided for, slackness in the leather or other suitable material of which the diaphragm is formed, is provided to allow for the movements of the vibrating member and too much slackness in the diaphragm makes the latter undesirable. Furthermore, a long stroke of the vibrating member at high speed is impracticable, owing to both the oscillation of and the slackness in the leather, and decreases the efficiency of the pump, creating a pocket which does not discharge proportionately the volume of air as you increase the length of the stroke. Furthermore, the kinking of the leather of the diaphragm, which is caused by its varying positions, incidental to a long stroke, would soon destroy the leather and in a long stroke you get greater weight and more inertia to overcome.

There are also limitations to the diameter of the diaphragm pump:

First. For the reason that as you increase the area of the vibrating member at a given vacuum, the pressure on the vibrating member increases in proportion to the increased area of the vibrating member, and this increased load contributes to vibration and the destruction of the pump and motor.

Second. The increased area of the vibrating member necessitates, owing to the greater load, heavier moving parts throughout, including connecting-rods and vibrating member, which causes increased oscillation and inertia which have to be overcome. It further requires a heavier leather in the diaphragm to such an extent as to make the durability of the leather diaphragm questionable under such increased loads. For the above mentioned reasons, in order to gain greater volume and increased working pressure, I have devised novel means whereby two or more diaphragm pumps of a practical size may be utilized, and in so far as I know the manner in which this is accomplished is entirely novel with me, and my claims are therefore to be construed with corresponding scope.

In both the embodiments of my invention I employ a pump unit located in the vacuum chamber and provided with a plurality of independent and freely communicating pulsation chambers, between which the motor is located to actuate a vibrating member for each pulsation chamber and the pumping mechanism and motor may be bodily removed from the casing as a unit.

Having thus described my invention I claim and desire to secure by Letters Patent, is:

1. In a device of the character described, the combination of an inclosure forming a vacuum chamber, a plurality of freely com-

municating pulsation chambers in communication with the vacuum chamber, a vibrating member for each of said pulsation chambers, actuating means for the vibrating members, and valve mechanism controlled by the said pulsation chambers.

2. In a device of the character described, the combination of an inclosure forming a vacuum chamber, a plurality of freely communicating pulsation chambers, one of said pulsation chambers being located within said vacuum chamber and in communication therewith, a vibrating member for each of said pulsation chambers, actuating means for the vibrating members, and valve mechanism controlled by the pulsation chambers.

3. In a device of the character described, the combination of an inclosure forming a vacuum chamber, a plurality of pulsation chambers one of which is in communication with said vacuum chamber, a tube connecting said pulsation chambers and forming free communication therewith, a vibrating member for each of said pulsation chambers, actuating means for the vibrating members, and valve mechanism controlled by the pulsation chambers.

4. In a device of the character described, the combination of an inclosure forming a vacuum chamber, two freely communicating pulsation chambers in communication with the said vacuum chamber, tubes forming a means of communication between said pulsation chambers, said tubes forming a means of support for one of said pulsation chambers, a base to support the other one of said pulsation chambers, a vibrating member for each of said pulsation chambers, actuating means for the vibrating members, and valve mechanism controlled by the pulsation chambers.

5. In a device of the character described, the combination of an inclosure forming a vacuum chamber, two freely communicating pulsation chambers in communication with the said vacuum chamber, tubes to rigidly hold said pulsation chambers together and forming a means of communication between said pulsation chambers, means for supporting said pulsation chambers within said inclosure, a vibrating member for each of said pulsation chambers, actuating means for the said vibrating members, and valve mechanism controlled by the pulsation chambers.

6. In a device of the character described, the combination of an inclosure forming a vacuum chamber, two freely communicating pulsation chambers in communication with the said vacuum chamber, tubes between said pulsation chambers, bolts to clamp said pulsation chambers against the ends of said tubes, said tubes forming a means of communication between said pulsation chambers, means for supporting said pulsation chambers within said inclosure, a vibrating member for each of said pulsation chambers, actuating means for the said vibrating members, and valve mechanism controlled by the pulsation chambers.

tion chambers within said inclosure, a vibrating member for each of said pulsation chambers, actuating means for the said vibrating members, and valve mechanism controlled by the pulsation chambers.

7. In a device of the character described, the combination of an inclosure forming a vacuum chamber, two freely communicating pulsation chambers in communication with the vacuum chamber, a vibrating member for each of said pulsation chambers, a motor, suitable connections between said motor and said vibrating members and valve mechanism controlled by the pulsation chambers.

8. In a device of the character described, the combination of an inclosure forming a vacuum chamber, two freely communicating pulsation chambers in communication with the vacuum chambers, a vibrating member for each of said pulsation chambers, a motor within the vacuum chamber, a shaft for said motor, eccentrics on said shaft, connecting-rods for said eccentrics and non-pivotedly secured to said vibrating members and valve mechanism controlled by the pulsation chambers.

9. In a device of the character described, the combination of an inclosure forming a vacuum chamber, two freely communicating pulsation chambers in communication with the vacuum chamber, a vibrating member for each of said pulsation chambers, a motor, a shaft therefor, eccentrics on said shaft, connecting-rods between said eccentrics and said vibrating members, said eccentrics being mounted upon said shaft in such a position that said vibrating members will be actuated simultaneously in opposite directions, and valve mechanism controlled by the pulsation chambers.

10. In a device of the character described, the combination of an inclosure forming a vacuum chamber, two freely communicating pulsation chambers in communication with the vacuum chamber, a vibrating member for each of said pulsation chambers, a motor, a bearing supporting said motor in central alinement with the said vibrating members, suitable connections between said motor and said vibrating members, and valve mechanism controlled by the pulsation chambers.

11. In a device of the character described, the combination of an inclosure forming a vacuum chamber, two freely communicating pulsation chambers in communication with the vacuum chamber, a vibrating member for each of said pulsation chambers each consisting of a solid disk and a flexible diaphragm connected therewith, a motor located intermediate said pulsation chambers, connecting-rods operatively connected between said motor and said disks and valve mechanism controlled by the pulsation chambers.

- 6
12. In a device of the character described, the combination of a casing forming a vacuum chamber, two freely communicating pulsation chambers in communication with the vacuum chamber and resiliently mounted therein, a motor, suitable connections between said motor and said vibrating members and valve mechanism controlled by the pulsation chambers.
13. In a device of the character described, the combination of a casing forming a vacuum chamber, two freely communicating pulsation chambers in communication with the vacuum chamber and yieldingly mounted therein, a casing forming a muffler, a motor, suitable connections between said motor and said vibrating members and valve mechanism controlled by the pulsation chambers.
14. In a device of the character described, the combination of a casing forming a vacuum chamber, two freely communicating pulsation chambers in communication with the vacuum chamber, a vibrating member for each pulsation chamber, a separating device in said vacuum chamber, a motor, suitable connections between said motor and said vibrating members and valve mechanism controlled by the pulsation chambers.
15. A pump having a plurality of pulsation chambers in free communication with each other, a pumping member for each pulsation chamber, valve mechanism for the pulsation chambers consisting of a single inlet and a single outlet valve, the inlet valve coöperating with one pulsation chamber and the outlet valve coöperating with the other pulsation chamber, and actuating means for said pumping members.
16. A pump having a plurality of pulsation chambers in free communication with each other, a pumping member for each pulsation chamber, valve mechanism for the pulsation chambers, actuating means for said pumping members and yielding means for supporting the pump whereby it is free to vibrate in any direction.
17. A pump having a plurality of pulsation chambers in free communication with each other, a pumping member for each pulsation chamber, valve mechanism for the pulsation chambers, actuating means for said pumping members, the actuating means and the pump being secured together to form a unit of structure and yielding means for supporting the pumping members and the actuating means therefor.
18. In a device of the character described, the combination of a casing forming a vacuum chamber, a separating device in said casing, a base, means for detachably securing said base and said casing together, a pulsation chamber forming part of said base, a motor mounted upon said base, a pulsation chamber supported above said motor within said vacuum chamber, tubes connecting the said pulsation chambers, each of said pulsation chambers having an opening formed therein, a disk positioned in each of the said openings formed in said pulsation chambers, a flexible diaphragm in each pulsation chamber having its outer edge secured to said pulsation chamber and its inner edge secured to said disk, a pair of connecting rods operatively connected with each of said disks and with the shaft of said motor, an inlet valve in one of said pulsation chambers, an outlet valve in the other one of said pulsation chambers and a chamber having restricted openings formed therein located adjacent to said outlet valve.
19. A pump having a plurality of pulsation chambers in free communication with each other, a pumping member for each pulsation chamber, valves for controlling the inlet and outlet to the pulsation chambers, an actuating shaft for the pumping members located between the pulsation chambers, and devices carried by said shaft for simultaneously moving the pumping members in opposite directions.
20. A pump having a plurality of pulsation chambers, tubes connecting said chambers and forming a free communication between the same, a pumping member for each pulsation chamber, valves for controlling the inlet and outlet to the pulsation chambers, an operating shaft located between said pulsation chambers, and devices carried by said shaft for simultaneously moving said pumping members in opposite directions.
21. In a device of the character described, the combination of a vacuum chamber, a pumping unit, a spring for yieldingly suspending said pumping unit from the top of said vacuum chamber, said vacuum chamber having an opening formed in the top thereof, a flexible diaphragm secured to the top of the vacuum chamber encircling said opening, a flexible diaphragm secured to said pumping unit and inclosing an opening formed in the top of said pumping unit and means for securing the adjacent edges of said diaphragms together to form a passageway.
22. In a device of the character described, the combination of a vacuum chamber, a plurality of pulsation chambers rigidly connected together and freely communicating one with the other, means for yieldingly supporting said pulsation chambers within said vacuum chamber, a flexible passageway communicating with one of said pulsation chambers, a motor mounted between said pulsation chambers, vibrating members operated by said motor and valve mechanism located in said pulsation chambers.
23. In a device of the character described,

the combination of a casing forming a vacuum chamber, a removable lid on said casing, a pumping unit yieldingly suspended from said lid, a flexible exhaust passageway leading from said pumping unit to an opening formed in said lid, a casing on said lid forming a muffler, an inlet pipe communicating with the lower part of said casing, a separating device secured in said casing, a detachable base forming the lower part of said casing, and a removable member in said base for cleaning the latter.

24. In a pump for vacuum cleaners, the combination with two pumping chambers in constant communication with each other, of reciprocating pumping devices limiting the pumping chambers upon opposite sides, whereby the suction strokes and the delivery strokes of said devices are in opposite directions, driving means connected to said devices so as to operate them simultaneously upon their suction strokes and their delivery strokes, a valve-controlled inlet passage to said chambers, and a valve-controlled outlet passage from said chambers.

25. In a vacuum cleaning apparatus, the combination with a vacuum chamber, of vacuum-creating means connected therewith and comprising a pair of air pumps spaced apart and operative simultaneously and in unison both to draw in or expel air, driving means located between and connected with each of the pumps to operate them in unison and simultaneously, a plurality of air passages, one or more connecting the vacuum chamber with one of the pumps for the air intake and one or more different air passages connecting said pumps, and valves for said pumps, one controlling the admission of air to both of the pumps and the other the exhaust of air from said pumps.

26. In a vacuum cleaning apparatus, the combination of a vacuum chamber, a vacuum-creating means connected therewith and comprising a pair of pumps spaced apart, driving means located between said pumps and operating the pumps in unison simultaneously to draw in or expel air, said pumps having a plurality of air passages, one or more forming an air intake passage and one or more connecting said pumps, and valve mechanism in one of said pumps separating the pulsation chamber from another compartment.

27. In a vacuum cleaning apparatus, the combination of a vacuum chamber, a vacuum-creating means connected therewith and comprising a pair of pumps spaced apart, driving means located between said pumps and operating the pumps in unison simultaneously to draw in or expel air, said pumps having a plurality of air passages, one or more forming an air intake passage and one or more connecting said pumps, a valve mechanism in one of said pumps sepa-

rating the pulsation chamber from another compartment, and another valve mechanism, one of said valve mechanisms controlling the intake of air and the other the exhaust thereof.

28. In a vacuum cleaning apparatus, the combination of pumping mechanism comprising a pair of pump chambers spaced apart, a diaphragm in each of said chambers, one or more tubes connecting said chambers, a motor located between said pumps and connected with the diaphragms, whereby they are operated in unison, an inlet and an outlet valve for said pump chambers, and a vacuum chamber having an inlet and connected with the pump chambers through the medium of said inlet valve.

29. In a vacuum cleaning apparatus, the combination of a supporting base, pumping mechanism supported thereby and comprising a pair of pump chambers spaced apart one above the other, one or more air tubes connecting said chambers and forming pillars for supporting the upper chamber, a diaphragm in each of said chambers, a motor supported on said base between said chambers and having a driving shaft provided with a pair of oppositely disposed eccentrics, connecting rods between said eccentrics and diaphragms, an inlet and an outlet valve for said chambers, and a vacuum chamber supported above said pump chambers and having an outlet communicating with said inlet valve.

30. In a vacuum cleaning apparatus, the combination of a supporting base, pumping mechanism supported thereby and comprising a pair of pump chambers spaced apart one above the other, one or more air tubes connecting said chambers and forming pillars for supporting the upper chamber, a diaphragm in each of said chambers, a motor supported on said base between said chambers and having a driving shaft provided with a pair of oppositely disposed eccentrics, connecting rods between said eccentrics and diaphragms, an inlet and an outlet valve for said chambers, said chambers having an outlet and an inlet, and a casing supported by said base and inclosing said pumping mechanism and having a vacuum chamber therein above said pump chambers and communicating with said inlet valve.

31. In a device of the character described, the combination of a casing forming a vacuum chamber, a pumping unit located within said vacuum chamber and including means for creating a vacuum in said chamber, non-rigid means for connecting the pumping unit with the exterior of the casing for expelling air therefrom, and means for yieldingly supporting said pumping unit.

32. In a device of the character described,

the combination of a casing forming a vacuum chamber, a pumping unit located within said vacuum chamber including a motor and a pulsation chamber, means for rigidly connecting said motor and said pulsation chamber, flexible means for connecting the pulsation chamber with the exterior of said casing, and means for yieldingly supporting said motor.

10 33. In a device of the character described, the combination of a casing forming a vacuum chamber, a pumping unit located within said vacuum chamber and including a pulsation chamber, a vibrating diaphragm forming one wall of said pulsation chamber, a motor, means for rigidly connecting the motor and said pulsation chamber, means for vibrating the diaphragm from said motor, flexible means for connecting the 15 pulsation chamber with the exterior of the casing, and means for yieldingly supporting said pumping unit in said vacuum chamber.

20 34. In a device of the character described, the combination of a casing forming a vacuum chamber, a pumping unit within said vacuum chamber, said pumping unit including a pulsation chamber, a motor, means for rigidly securing said motor to said pulsation chamber, said pulsation chamber having a vibrating diaphragm, means for actuating said diaphragm from said motor, said pulsation chamber having a valve inlet leading to said vacuum chamber, and a valve outlet, flexible means for connecting said valve outlet with the exterior of said casing, and means for yieldingly supporting said pumping unit.

25 35. In a device of the character described, the combination of a cylindrical casing, a bottom member having an air tight connection with the lower end of said casing and a top member having an air tight connection with the upper end of said casing and forming therewith a vacuum chamber, one of said members having an inlet and the other member having an outlet leading to the exterior of said casing, a pumping unit located within said casing, said pumping unit 30 including a pulsation chamber having a valve outlet, flexible means for connecting said valve outlet with the outlet leading to the exterior of said casing, said pumping unit also including a motor rigidly connected with the pulsation chamber, said pulsation chamber having a vibrating diaphragm, means for actuating the same from said motor, and means for supporting said pumping unit in said vacuum chamber, whereby 35 the same may yield vertically to the vibrations of the pumping unit.

40 36. In a device of the character described, the combination of a cylindrical casing, a bottom member having an air tight connection with the lower end of said casing and a

top member having an air tight connection with the upper end of said casing and forming therewith a vacuum chamber, one of said members having an inlet and the other member having an outlet leading to the exterior of said casing, a pumping unit located within said casing, said pumping unit including a pulsation chamber having a valve outlet, flexible means for connecting said valve outlet with the outlet leading to the exterior of said casing, said pumping unit also including a motor rigidly connected with the pulsation chamber, said pulsation chamber having a vibrating diaphragm, means for actuating the same from said motor, means for supporting said pumping unit in said vacuum chamber, whereby the same may yield vertically to the vibrations of the pumping unit, and a separator within said casing and extending from wall to wall thereof between the inlet to said casing and said pumping unit.

45 37. In a device of the character described, the combination of a cylindrical casing, a bottom member having an air tight connection with the lower end of said casing and a top member having an air tight connection with the upper end of said casing and forming therewith a vacuum chamber, one of said members having an inlet and the other member having an outlet leading to the exterior of said casing, a pumping unit located within said casing, said pumping unit including a pulsation chamber having a valve outlet, flexible means for connecting said valve outlet with the outlet leading to the exterior of said casing, said pumping unit also including a motor rigidly connected with the pulsation chamber, said pulsation chamber having a vibrating diaphragm, means for actuating the same from said motor, means for supporting said pumping unit in said vacuum chamber, whereby the same may yield vertically to the vibrations of the pumping unit, and a muffler for the outlet from said casing.

50 38. In a device of the character described, the combination of a casing forming a vacuum chamber, a pumping unit located within said vacuum chamber and including two pulsation chambers rigidly connected together and having valve connections with said vacuum chamber, a flexible diaphragm for each pulsation chamber, a motor having its supporting base rigidly connected to said pulsation chambers, means for vibrating said diaphragm from said motor, non-rigid means for connecting the pulsation chamber with the exterior of the casing, and means for supporting said pumping unit in said vacuum chamber, whereby the same may yield vertically to the vibrations of the pumping unit.

55 39. In a device of the character described, the combination of a casing, a pumping unit

located within said casing, including a motor and a pulsation chamber, means for rigidly connecting said motor and said pulsation chamber, means for connecting the pulsation chamber with the exterior of said casing, and means for yieldingly supporting said motor and pulsation chamber, said means for connecting said chamber with the exterior of the casing being so constructed

as to permit the motor and pulsation chamber to move freely on its yielding supporting means. 10

In testimony whereof I affix my signature in presence of two witnesses.

HOWARD SMALL.
